DUPLEX VEHICLE SEAT

Walter B. Dean, Narberth, and Richard M. Irwin, Philadelphia, Pa., assignors to The Budd Company, Philadelphia, Pa., a corporation of Pennsylvania

Application January 29, 1957, Serial No. 44,652

Term of patent 14 years

(Cl. D15—8)

FIG. 1

FIG. 3

FIG. 2

FIG. 4

Fig. 1 is a front angled perspective view of a duplex vehicle seat, showing our new design;

Fig. 2 is a rear perspective view of the seat;

Fig. 3 is a side elevation; and

Fig. 4 is a horizontal section taken on the line 4—4 of Fig. 2.

We claim:

The ornamental design for a duplex vehicle seat, substantially as shown.
